Patented Jan. 31, 1922.

UNITED STATES PATENT OFFICE.

THEODOR KOZLOSKY AND EDWARD C. KOSTOWSKI, OF TOLEDO, OHIO.

RAIL JOINT.

1,404,976.

Specification of Letters Patent. Patented Jan. 31, 1922.

Application filed July 12, 1921. Serial No. 484,135.

To all whom it may concern:

Be it known that we, THEODOR KOZLOSKY and EDWARD C. KOSTOWSKI, citizens of Poland and of the United States, respectively, residing at Toledo, in the county of Lucas and State of Ohio, have invented certain new and useful Improvements in Rail Joints, of which the following is a specification.

This invention relates to rail joints and it has for a general object to provide a novel and efficient rail joining means which will obviate the use of fish-plates and bolts.

More specifically speaking the invention has for an object to provide a spring actuated locking device which is entirely concealed when in use within the rail body.

For further comprehension of the invention, and of the objects and advantages thereof, reference will be had to the following description and accompanying drawings, and to the appended claims in which the various novel features of the invention are more particularly set forth.

Fig. 1 of the drawings is a plan view of a pair of separated rail ends provided with our improved joining means.

Fig. 2 is a part side view and part longitudinal sectional view, of the rail ends, the sectional portion of the view being taken on the line 2—2 of Fig. 1.

Fig. 3 is a plan view of a portion of a track having the invention applied thereto.

Fig. 4 is a part elevation and part longitudinal section on the same line as Fig. 2, but showing the rails joined.

Referring now to the drawings, the reference numerals 10 and 11 indicate a pair of rail ends. According to the present invention the tread 10' of the rail 10 is cut off at a distance from the end, while the web 10^a is widened considerably to form a block 12. This block has a pair of slotted recesses 13 formed on the underside thereof and communicating both with the bottom and end of the block.

These recesses 13 present downwardly and rearwardly inclined top walls such as 13' and have upwardly offset sockets 14 near their inner ends.

The rail 11 has the web portion of the end thereof widened as at 15 to approximately the width of the block 12, the main body 11^a of the web terminating short of the tread 11' a distance corresponding to the cut out in the end of the tread 10' of rail 10, leav-

ing a projecting tread element 11^b which extends over the block 12.

The rail 11 has projected forwardly therefrom a pair of tongues 18 which are flush on their bottom sides with the base of the rail 60 and are shaped to fit in the recesses 13 in block 12, presenting inclined top faces 18' corresponding to the inclined tops 13' of said recesses.

To lock the rail ends against longitudinal 65 movement away from one another I provide in each tongue 18 a latch 20 pivoted between its ends as at 21 in a recess 22 in said tongue and having an upturned end 20' normally pressed into the socket 14 by a spring 70 23, the different parts being so arranged that the latch ends 20' will enter the open end of recesses 13 when the rails are moved longitudinally toward one another and will be pressed downward by the inclined surfaces 13' until they snap into the sockets 14. To enable the latches 20 to be depressed to be disengaged from the sockets 14 when the rail ends are being disassembled, a pair of 75 small passages 24 lead downward through 80 the block 12 into the sockets 14 and are adapted to have a pin or other suitable implement inserted therein to depress the latches.

Additional locking means for the rail 85 ends is provided in the form of a pair of vertical bolts such as 26 slidable in recesses such as 27 in the block 12 and each having a T-head 28 adapted to be projected downward into a socket 29 in the tongue 18 and given 90 a partial turn to cause its head 28 to engage in offsets 30 from said socket. These bolts 26 are pressed upwardly to cause their T-heads to clear the sockets by means of coiled springs such as 31 surrounding the same 95 and bearing against flanges such as 32 on the bolt, the latter having squared upper ends such as 33 to receive a wrench or spanner for turning the bolts to enter the heads 28 in the offsets 30.

The bolts 26 are preferably covered by means of plates 35 slidable in dovetail grooves such as 36 in the top face of block 12, the squared upper ends of said bolts being sunk below the top of said block when 105 the T-heads 28 are engaged in the offsets 30.

It is believed that the manner of assembly and operation of our improved rail joining means will be readily understood from the foregoing description.

100

105

110

The plates 35 are drawn back in the grooves 36 to allow the springs 31 to raise the heads 28 of bolts 26. The two rails are then moved longitudinally into engagement, 5 the tongues 18 engaging in the recesses 13, the latch ends 20' being depressed by engagement with the inclined walls 13' until they snap into the sockets 14. The bolts 26 are then pushed downward and given a quarter turn to engage their T-heads in the offsets 30 and the plates 35 replaced.

Having thus described our invention what we claim as new and desire to protect by Letters Patent of the United States is as follows:—

1. In combination, a pair of rail ends one of which has the tread terminating short of the end thereof and a widened block-like extension presenting a pair of recesses, the 20 other rail end having a projecting tread element engaging over said extension and a pair of tongues engaging in said recesses.

2. In combination, a pair of rail ends one of which has the tread terminating short of the 25 end thereof and a widened block-like extension presenting a pair of recesses, the other rail end having a projecting tread element engaging over said extension and a pair of tongues engaging in said recesses,

30 and latches carried by said tongues and engaging in sockets offset from said recesses.

3. In combination, a pair of rail ends one of which has the tread terminating short of the end thereof and a widened block-like 35 extension presenting a pair of recesses, the other rail end having a projecting tread element engaging over said extension and a pair of tongues engaging in said recesses, and latches carried by said tongues and 40 engaging in sockets offset from said recesses, the said block having passages leading therethrough to the said sockets.

4. In combination, a pair of rail ends one of which has the tread terminating short of the 45 end thereof and a widened block-like extension presenting a pair of recesses, the other rail end having a projecting tread ele-

ment engaging over said extension and a pair of tongues engaging in said recesses, said tongues having sockets in their upper 50 faces presenting interior offsets, and T-headed bolts carried by said extension and adapted to engage in said offsets.

5. In combination, a pair of rail ends one of which has the tread terminating short of the 55 end thereof and a widened block-like extension presenting a pair of recesses, the other rail end having a projecting tread element engaging over said extension and a pair of tongues engaging in said recesses, 60 and locking means carried by said block and tongues and comprising a pair of latches and a pair of T-headed bolts.

6. In combination, a pair of rail ends one of which has the tread terminating short of the 65 end thereof and a widened block-like extension presenting a pair of recesses, the other rail end having a projecting tread element engaging over said extension and a pair of tongues engaging in said recesses, 70 said tongues having sockets in their upper faces presenting interior offsets, and T-headed bolts carried by said extension and adapted to engage in said offsets, and slide- 75 able plates on said block adapted to cover said bolts.

7. In combination, a pair of rail ends one of which has the tread terminating short of the end thereof and a widened block-like extension presenting a pair of recesses, the 80 other rail end having a projecting tread element engaging over said extension and a pair of tongues engaging in said recesses, and latches carried by said tongues and en- 85 gaging in sockets offset from said recesses, said recesses having inclined faces adapted to engage and depress said latches, and springs normally urging said latches upward to locking position.

In testimony whereof we have affixed our 90 signatures.

THEODOR KOZLOSKY.
EDWARD C. KOSTOWSKI.
